UNITED STATES PATENT OFFICE.

ASHLEY J. GULICH, OF CLEARFIELD, PENNSYLVANIA, ASSIGNOR TO THE
PERFECTION KNITTING MACHINE COMPANY, OF SAME PLACE.

CIRCULAR-KNITTING MACHINE

SPECIFICATION forming part of Letters Patent No. 656,155, dated August 14, 1900.

Application filed March 30, 1899. Serial No. 711,132. (No model.)

To all whom it may concern:

Be it known that I, ASHLEY J. GULICH, a citizen of the United States, residing at Clearfield, in the county of Clearfield and State of Pennsylvania, have invented a new and useful Tension Device for Circular-Knitting Machines, of which the following is a specification.

This invention relates to tension devices for circular-knitting machines; and the object in view is to provide an improved construction of yarn-carrier having a novel form of self-adjusting or automatic take-up, whose tension automatically varies according to the use of the machine and the requirements of the feed.

With this and other objects in view, which will readily appear as the nature of the invention is better understood, the same consists in the novel construction, combination, and arrangement of parts hereinafter more fully described, illustrated, and claimed.

While the essential features of the invention are necessarily susceptible to modification, still the preferred embodiment thereof is shown in the accompanying drawings, in which—

Figure 1 is a perspective view of a circular-knitting machine of the gear-operated type fitted with the improvements contemplated by the present invention. Fig. 2 is a vertical sectional view of the machine shown in Fig. 1, the line of section being at one side of the plane of the yarn-carrier which is used with the gear-operated machine. Fig. 3 is a detail in perspective of the revoluble cam ring or head shown removed from the base-ring or cylinder. Fig. 4 is a fragmentary sectional view of the cam-ring, showing the arrangement and relative positions of the needle-controlling cam. Fig. 5 is a vertical sectional view of the crank-operated type of machine, having the cam ring or head thereof fitted with certain of the improvements contemplated by the present invention. Fig. 6 is a detail sectional view on the line 6-6 of Fig. 4.

Referring to the accompanying drawings, the numeral 1 designates the horizontal base-ring of the machine, provided at one side thereof with the usual clamp 2 for securing the same to a table, shelf, or similar support. The said base-ring is formed at its inner

peripheral edge with an annular guide rabbet or groove 3 and has projected inwardly from the inner side thereof a plurality of arched supporting-arms 4, to which is rigidly fastened the lower end of the upright needle-cylinder 5, thereby providing a rigid connection between the cylinder and the base-ring, similar to the connection shown in my former patent, No. 560,712. The upright stationary needle-cylinder 5 is of the ordinary construction, being provided in its exterior face with a circumferential series of vertically-disposed needle channels or grooves 6, in which reciprocate the vertically - movable knitting-needles 7, which needles are retained within their guide channels or grooves in the ordinary manner and are provided at their lower ends with the usual outwardly-disposed heel projections 8, which travel on the track formed by the upper edge 9 of the revoluble cam ring or head 10. The revoluble cam ring or head 10 loosely encircles the needle-cylinder 5 at the lower end of the latter and is provided at its lower edge with an outturned bearing-flange 11, which loosely registers in the annular guide rabbet or groove 3 at the inner peripheral edge of the base-ring, and said bearing-flange 11 of the cam ring or head is detachably retained in a working position by means of the plurality of retaining-plates 12, detachably fastened to the upper side of the base-ring and having their inner edges overlapping the peripheral edge of the flange 11, such construction being similar to that disclosed in my pending application, Serial No. 685,500.

Certain of the improvements contemplated by the present invention are applicable not only to the gear type of machine disclosed in my former patent, but also to the gearless or crank-operated machine covered by the pending application referred to; but reference will first be made to these improvements associated with the gear-operated machine shown in Figs. 1 and 2 of the drawings.

In the type of machine referred to the revoluble cam ring or head 10 is provided at its lower edge with a circular gear portion or member 13, with which meshes the drive gear-wheel 14, mounted on the inner end of a short operating-shaft 15, arranged below

the plane of the base-ring and journaled in the pendent bearing-bracket 16, fitted to the base-ring at one side thereof, and said short operating-shaft 15 has mounted on the outer end thereof a crank-handle 17, which is grasped by the operator to provide for rotating the revoluble cam ring or head, and thereby reciprocating the vertically-movable knitting - needles. Substantially the same means are disclosed in my former patent to provide for communicating motion to the revoluble cam ring or head; but in the present invention said cam ring or head is designed to have the needle-controlling cams arranged and supported in a novel manner, whereby the entire set of cams may be adjusted vertically to permit of tight or loose knitting. This is accomplished through the medium of a vertically-adjustable segmental cam-supporting plate 18, which plate is fitted to the outer face of the cam ring or head at one side of the vertical center thereof and forms an inclosing wall for the pair of spaced approximately V-shaped cam - recesses 19, formed in the body of the cam ring or head at one side thereof, and having their edges forming direct continuations of the main upper track edge 9 of the cam ring or head, which lies in a horizontal plane more than one-half the circumference of the said ring or head.

Associated with spaced V-shaped cam-recesses 19 of the cam ring or head and the vertically-adjustable segmental cam-supporting plate 18 are the needle actuating or controlling cams 20, 21, and 22, which are fitted to the inner concaved side of the cam-supporting plate. The main needle-controlling cam 20 is rigidly fastened to the inner side of the cam-supporting plate near the top edge of the latter and extends substantially from end to end thereof. The said main cam 20 has substantially the same configuration as the corresponding cam shown in my former patent, No. 560,712, with the exception that the central downwardly-pointing V-shaped or triangular lobe 23 lies in substantially the same plane as the rounded terminal lobes of the cam, so as to be disposed directly above the short elevated track - section 24, lying between the cam-recesses 19. The cams 21 and 22 are respectively the right and left switch cams or dogs and are pivoted at their inner ends, as at 25, to the inner side of the cam-supporting plate 18, respectively at opposite sides of the downwardly-pointing center lobe 23 of the main cam 20, said switch-cams 21 and 22 being of an approximately -triangular configuration and normally loosely projecting into the V-shaped cam-recesses 19. All of the said cams 20, 21, and 22 are arranged above and in the vertical plane of the upper edge track portion of the cam ring or head to form sinuous passages for the travel of the heel projections 8 of the reciprocating needles. The operation of the cams is familiar to those skilled in the art;

but it may be explained at this point that as the cam-ring is rotated in one direction the heel projections of the needles will enter between one of the switch-cams and the adjacent edge of the main cam 20 and pass out of the cam-space between the other or opposite switch-cam and the adjacent track edge within one of the V-shaped cam-recesses 19, 75 as plainly illustrated in Fig. 4 of the drawings. When the rotation is reversed, the position of the dogs must also be reversed, which can be accomplished by the proper manipulation of the needles in the usual way, as 80 fully explained in my former patent herein referred to; but it will be understood that by reason of providing the cam ring or head with a pair of cam-recesses, one, respectively, for each of the switch-cams, the needles are 85 more positively and uniformly reciprocated and are caused to take hold of the yarn and free themselves therefrom with greater facility than has heretofore been possible.

To provide for slidably mounting the cam-supporting plate 18 upon the cam ring or head, said plate is provided centrally between its ends with a vertically-disposed slot 26, leading upward from its lower edge and slidably engaging a vertically-disposed guide-rib 27, projecting integrally from the outer side of the cam ring or head and provided with a threaded opening receiving a pivot-screw 28, on which is loosely mounted one end of a curved adjusting-lever 29. The said curved adjusting-lever 29 is provided at one end with a finger-plate 30 and intermediate its end with a longitudinally-disposed slot 31, receiving a clamping-screw 32, engaging in a threaded opening formed in the cam-supporting plate. By loosening the screw 32 and manipulating the lever 29 the cam-supporting plate 18 and the entire set of cams carried thereby may be raised or lowered to any desired degree to provide for causing tight or loose stitching, as may be required, and after being adjusted to its set position the said cam-supporting plate is held rigid in such position by simply tightening the clamping-screw, as will be readily understood.

The vertically-adjustable cam-supporting plate 18 has projected integrally from the top edge thereof and centrally between its ends an upwardly-disposed and laterally-offset bracket-arm 33, which is provided at its extreme upper end with a supporting-head 34, having formed therein a seat-groove 35, in which is adjustably fitted a longitudinally-slotted stem 36, projected integrally from the outer side of an approximately -triangular bowed yarn-guide plate 37. The longitudinally-slotted stem 36 of the yarn-guide plate is adapted to receive a clamping-screw 38, engaging in a threaded opening forming the upper end of the bracket-arm and providing means for securing the yarn-guide plate in any adjusted position toward and away from the needles within the needle-cylinder. The said yarn-guide plate is arranged in a plane

just above the top edge of the needle-cylinder and is also disposed in close proximity to the vertical plane of the reciprocating needles, so as to provide for positively and uniformly delivering the yarn to the hooks of the needles as the cam ring or head revolves about the needle-cylinder, and to insure this result the yarn-guide plate is provided therein at the lower side thereof with a guide opening or eye 39, through which the yarn 40 passes to the hooks of the needle, and said yarn is carried to the opening or eye 39 through the guide-opening 40^a, formed in the guide-stem 38 contiguous to the outer side of the bowed yarn-guide plate 37.

In the gear-operated type of machine just described the yarn is delivered to the guide carried by the revoluble cam ring or head from a fixedly-positioned or stationary yarn-carrier 41, which is supported on the base-ring 1, preferably at the side thereof carrying the clamp 2. To provide for the proper support of the yarn-carrier, there is employed a supporting-bracket 43, provided at its lower end with a slotted foot 44, detachably fastened to the upper side of the base-ring 1 by means of the fastening-screw 44^a. The said supporting-bracket 43 is extended upwardly and outwardly from its point of connection with the brace-ring and has detachably fitted in the upper outer end thereof a horizontal bobbin-spindle 45, extending beyond both sides of the supporting-bracket 43 and receiving, respectively, upon the opposite portions thereof the oppositely-located yarn bobbins or spools 46, from either of which the yarn 40 may be strung through the yarn-carrier and the yarn-guide carried by the revoluble cam ring or head.

At one side of the plane of the horizontal bobbin-spindle 45 the supporting-bracket 43 is provided therein with a vertically-disposed opening 47, in which is adjustably secured the lower end of the upright yarn-carrier standard 48, to the upper end of which standard is fitted a horizontal cross-arm 49, the inner end portion of which overhangs the needle-cylinder to provide for the proper feeding of the yarn to the yarn-guide of the cam ring or head. The said cross-arm 49 is provided in each end thereof with a guide-opening 50, and at a point intermediate the carrier-standard and the inner end of the cross-arm the latter has mounted thereon the yarn-lock

51. The yarn-lock 51 is provided at one terminal with a guide-eye 52 and is bent at its opposite end into a lock-loop 53, extending over or straddling the cross-arm 49. At the looped end 53 thereof the yarn-lock 51 is pivoted to the said cross-arm 49, so that it can readily swing up and down to either bind the yarn on top of the cross-arm or to allow the yarn to pass through the guides freely to the needles.

Associated with the yarn-lock 51 is a self-adjusting take-up wire 54, which is pivotally mounted contiguous to one end on the pivot-

pin 55, fitted in one side of a pivot ear or lug 56, projected integrally from the upper side of the cross-arm, substantially in the vertical plane of the yarn-carrier standard 48. The long arm of the self-adjusting take-up wire 54 is provided at its terminal with a coiled guide-eye 56^a, which receives the yarn 40 from the guide-eye 52 at one terminal of the yarn-lock, and from the terminal guide-eye 56^a of the take-up wire the yarn passes through the guide-opening 50 in the inner end of the cross-arm, and from thence to the yarn-guide carried by the cam ring or head. The short arm 80 of the said self-adjusting take-up wire is formed into an oblong or elongated loop 57, which, mechanically speaking, provides a longitudinally-disposed slot which slidably receives the connecting-eye 58, formed at the upper end of a retractile spring 59, the lower end of which spring is detachably engaged with the hook 60 at one end of the adjusting-arm 61, adjustably fastened to the yarn-carrier standard 48, to provide means for varying the tension of the spring.

When the machine is being operated one way and there is a steady drag upon the yarn, the long arm of the take-up wire 54 is depressed in a close relation to the upper side 95 of the cross-arm 49, and as the said take-up wire passes to this position the connecting-eye 58 at the upper end of the spring 59 slides within the loop 57 close to the pivot-center of the take-up wire, thereby lightening the tension on said wire, so that the yarn may be freely drawn from the carrier to the guide of the cam ring or head, and in this position of the take-up wire there is also no strain in an upward direction on the yarn-lock, so that the lock-loop thereof will not bind on the yarn. However, when only a portion of the needles are in operation, as when knitting the heel or toe of hosiery or in knitting web form, the cam ring or head is moved back and forth, which necessarily slackens up the yarn, and thereby permits the take-up wire to spring to an elevated position, which consequently elevates the yarn-lock and causes the lock-loop thereof to pinch the yarn on top of the cross-arm. The take-up wire then serves to take up the slack in the yarn without drawing the latter from the bobbin which is in use, and at this point it will also be observed that as the take-up wire springs to its elevated position the connecting-eye 58 of the retractile spring slides into the end of the loop 57, away from the pivot-center of the take-up wire, and thereby increases the tension on said wire, which is necessary to insure a proper operation of the yarn-lock. It will thus be seen that the take-up wire has the tension thereof automatically varied according to the use of the machine.

In the modification of the invention shown in Fig. 5 of the drawings certain of the improvements herein described are shown applied to the gearless or crank-operated type of machine covered by my aforesaid pending

application, Serial No. 685,500. In the modification referred to the use of gears is entirely dispensed with, and to provide for rotating the revoluble cam ring or head an offset standing crank arm or lever 62 is employed. The said crank arm or lever 62 is provided at its upper end with a vertically-arranged hand-grasp 63 and at its lower end with an attaching-foot 64, adapted to be detachably fastened by means of the fastening-screw 65 to the outer side of the bracket-arm 33 below the plane of the supporting-head 34 at the upper end thereof. In other respects the mounting of the cam-supporting plate and cams is the same as previously described, with the exception that in order to provide for properly feeding the yarn to the yarn-guide plate 37 the latter is preferably provided at the upper side thereof above the plane of the guide opening or eye 39 with an extra guide opening or eye 39^a for receiving the yarn from the yarn-carrier 41^a. The yarn-carrier 41^a is the form of yarn-carrier that must be used with the cam ring or head when the latter is rotated by means of a crank arm or lever rigidly connected therewith and is fastened directly to the cam ring or head, so as to rotate therewith in the manner fully disclosed in my aforesaid application. The said yarn-carrier 41^a comprises the same elements as described in said application—namely, the take-up wire 65 and the yarn-lock 51; but in the present invention the yarn-carrier standard 67 instead of being connected to the supporting-bracket 43 by means of a vertical pivot, as disclosed in said application, is connected to said supporting-bracket by a horizontal pivot 68, which permits of the yarn-carrier standard and the parts carried thereby being swung in a radial direction outwardly away from the needle-cylinder when threading or adjusting the parts of the machine in and around the needle-cylinder.

In the modification shown in Fig. 5 the supporting-bracket 43 is also fitted with the bobbin-spindle 45, carrying the pair of oppositely-arranged yarn bobbins or spools 46.

The usual weighted work-holding spider 69 is engaged with the fabric being knitted to provide for placing a proper tension thereon.

The many advantages of the invention will be readily appreciated by those skilled in the art without further description, and I will have it understood that changes in the form, proportion, size, and the minor details of construction within the scope of the appended claims may be resorted to without departing from the spirit or sacrificing any of the advantages of this invention.

Having thus described the invention, what is claimed as new, and desired to be secured by Letters Patent, is—

1. In a circular-knitting machine, the com-

bination with a knitting-cylinder and a yarn-carrier, of a cross-arm on the carrier, a yarn-lock connected to and freely movable on said cross-arm and provided with a guide-eye, a take-up arm normally elevated above the cross-arm and supported by the yarn-carrier in co-operative relation to the yarn-lock, said take-up arm having a yarn-guide eye and pivotally mounted on the yarn-carrier, and an automatically-adjustable tension device having a slidable connection with said take-up arm to vary the tension exerted thereby according to the slack or feed of the yarn.

2. In a circular-knitting machine, the combination with a knitting-cylinder and a yarn-carrier, of a cross-arm on the carrier, a take-up arm normally elevated above the cross-arm and having a yarn-guide eye and mounted pivotally on the yarn-carrier, and an automatically-adjustable tension-spring having a slidable connection with said take-up arm to vary the tension exerted on the yarn by the take-up arm according to the feed or slack in the yarn, substantially as described.

3. In a circular-knitting machine, the combination with a knitting-cylinder, a yarn-carrier, and a yarn-lock supported on said carrier, of a self-adjusting take-up arm pivoted on the carrier and having a slot and a guide-eye, the latter being in operative relation to the yarn-lock, and a tension-spring having a shiftable connection with the slotted part of the take-up arm, substantially as described.

4. In a circular-knitting machine, the combination with the knitting-cylinder and the cam ring or head, of a yarn-carrier having a yarn-lock, a self-adjusting take-up wire mounted for movement independently of and co-operating with said lock, and a tension-spring having a slidable self-adjusting connection with said take-up wire to vary the tension or stress thereof, substantially as set forth.

5. In a knitting-machine, the combination with the needle-cylinder and the cam ring or head, of a yarn-carrier having a standard carrying a horizontal arm at its upper end, a yarn-lock mounted on said horizontal arm, a take-up wire pivotally supported contiguous to one end on said horizontal arm and co-operating with the yarn-lock, said take-up wire having the short arm thereof at one side of its pivot formed with a longitudinally-disposed slot, and a tension-spring having a fixed support at one end, and having its other end slidably engaged in said slot, substantially as set forth.

In testimony that I claim the foregoing as my own I have hereto affixed my signature in the presence of two witnesses.

ASHLEY J. GULICH.

Witnesses:
